UNITED STATES PATENT OFFICE.

THEODOR REHBOCK, OF KARLSRUHE, GERMANY.

SPILLWAY APRON.

Application filed March 30, 1925. Serial No. 19,468.

To all whom it may concern:

Be it known that I, Dr. THEODOR REHBOCK, a citizen of Germany, residing at Karlsruhe, Baden, Germany, have invented 5 certain new and useful Improvements in Spillway Aprons (for which I have filed an application for patent in Germany, April 10th, 1924), of which the following is a specification.

10 The fall of water rushing over platforms and weirs or passing under flood-gates produces flowing-off velocities surpassing the speed of waves, so that the water passes from the normal or "flowing" course to the 15 so-called "shooting" state which has a specially destructive effect on the river bed. Various means have been applied in order to lead back the shooting course of the water to the normal flowing, viz: to velocities slower 20 than that of waves.

These means consist either of deepened water cushions receiving the shock of the fall, or of aprons containing several bays, a 25 number of partition walls disposed in the direction of the running water parallel to each other, or a system of grill-shaped sills 30 surmounting the bottom at the same height with interposed ditches. All these means serve to change the shooting current into a flowing course by transforming the considerable quantity of kinetic energy contained 35 in the stream into thermal energy.

When the water course below the fall has a sufficient depth, these expensive constructions, which render difficult the movement of sediments, can be spared. For even on a totally smooth and even apron the water forms above the shooting stream a surface 40 eddy with a horizontal axis transverse to the stream transforming the kinetic energy of the water by friction into thermal energy on a short distance, so that the water in leaving the surface eddy after having lost the greatest part of its kinetic energy runs 45 "flowing" with a medium speed corresponding to that of the normally running stream. This has been proved by trials on models and by observation of nature.

Local scouring out of the bottom may however be observed in the bed below the end of the surface eddy, which do not appear in other parts of rivers or channels with the same average speed. This is due to the fact that while in a normal stream the speed in 50 the lower part of the cross-section near the bottom is considerably less than the average

speed, owing to the continuous friction along the bed, in the water-course down-stream of the eddy the speed decreases from the bottom to the surface of the water-course, 60 owing to the strong withdrawal of energy being produced on the surface of the stream by the eddy, so that the current velocity in the vicinity of the bed surpasses the medium velocity of the whole stream, and thus produces washings-out of the bed. 65

The object of my invention is to remove this pernicious repartition of the current velocities from the cross-sections of the stream down-stream from the surface eddy as 70 quickly as possible. I attain this object by the means shown in the accompanying drawings, in which—

Fig. 1 is a perspective view seen up-stream of that part of a river-bed situated immediately down-stream a water-fall, a weir or a flood-gate and provided with the means according to the invention. Fig. 2 is a longitudinal section of a part of a river-bed comprising a water-fall and the down-stream 80 adjacent course. Fig. 3 is a similar longitudinal section of a part of a bed comprising a flood-gate and the up- and down-stream adjacent courses. Fig. 4 shows the right hand part of Figs. 2 and 3 on an enlarged scale. 85

At the extreme down-stream end of the usual even apron *a* protecting the bed *b* immediately down-stream the fall *c*, Fig. 2, or the gate *d*, Fig. 3, there is disposed a 90 low roof-shaped sill *e* formed integrally with the apron *a*. This sill is on the up-stream side of its upper face provided with a series of teeth *f* with a vertical up-stream face and a gently sloping down-stream face. 95

On the apron *a* the water forms above the shooting current *g* a surface eddy *h* with a horizontal axis transverse to the stream. As shown in Figs. 2, 3 and 4, the sill *e* is situated at the exit of the water from this surface eddy. Thus the rapidly flowing part of the stream in the vicinity of the bed *b* is by means of the toothed sill *e*—*f* gently deviated upwards. The surface velocities which cannot injure the bed are in this 105 manner intensified, whilst the dangerous velocities in the vicinity of the bed are correspondingly slowed down. At the same time a ground eddy *i* is formed below the water-course on the unprotected part of the 110 bed *b* down-stream the apron *a*, the lower part of which eddy flowing just over the

ground is directed up-stream. Thin jets of water running down-stream through the gaps between the teeth f discharge themselves into the up-stream current of this ground eddy expanding in shape of a fan. The current velocities in the lower part of the ground eddy are thereby slowed down to a quiet stream which cannot affect seriously even the unprotected part of the bed b . Thus the ground eddy i prevents the bed from being washed-out and even produces alluvions near the sill e , as has been proved by numerous trials. The gently ascending streams of water flowing through the gaps between the teeth f prevent the main current from descending too rapidly to the bed and from affecting thereby the ground. The gaps also serve to let pass the sediments. In order to lessen still more effectively the particularly pernicious excavations along the banks or side-walls k , Fig. 1, of the bed, the teeth f^1 at both ends of the sill e may have a greater width and height than the other teeth f .

The line $x-y$ in Fig. 4 indicates the passage from the shooting current g to the flowing course l . z , Figs. 2 and 4, is the energy-line.

What I claim as my invention and desire to secure by Letters Patent is:

1. In combination with a spillway apron, a low sill disposed at the extreme down-stream end of said apron and at the exit of the water from the surface eddy formed by the water on said apron, said sill being provided with a series of teeth having a steeply inclined face directed up-stream.

2. In combination with a spillway apron, a low roof-shaped sill disposed at the extreme down-stream end of said apron and at the exit of the water from the surface eddy formed by the water on said apron, said sill being provided on the up-stream side of its upper face with a series of teeth having a steeply inclined up-stream face and a gently sloping down-stream face.

In testimony whereof I affix my signature.
Dr. Ing. THEODOR REHBOCK.
